UNITED STATES PATENT OFFICE.

JULIA B. FRENCH, OF BOSTON, MASSACHUSETTS.

COMBINED WASH AND BATH TUB.

SPECIFICATION forming part of Letters Patent No. 317,333, dated May 5, 1885.

Application filed May 22, 1884. (No model.)

To all whom it may concern:

Be it known that I, JULIA B. FRENCH, of Boston, in the county of Suffolk and State of Massachusetts, have invented a new and useful Improvement in a Combined Wash and Bath Tub, which improvement is fully set forth in the following specification.

The present invention relates to that class of wash-tubs which are arranged in sets, with removable partitions between the different tubs, so that at will they may be converted into a single tub or vessel for bathing or for other purposes.

The invention comprises certain improvements in this class of tubs, which will be described in connection with the accompanying drawings, which form a part of this specification.

Figure 1 is a perspective view; Fig. 2, a vertical section through one of the partitions, and Fig. 3 a vertical section of the head-rest.

The removable partitions *a*, by which the vessel is divided into three compartments, are provided along their sides and bottom with a packing, *b*, of any suitable kind, which may be let into the edge of the wooden partition.

The fastening devices for securing the partitions in place consist of a plate, *c*, pivoted at one end to the top of the tub and at the other carrying a set-screw, *d*. By properly turning the screws *d*, which bear upon the tops of the partitions *a*, the latter are forced into place, making a tight joint with the sides of the tub. To secure accurate disposition of the partitions, they may be provided with dowel-pins, *e*, entering holes in the bottom of the tub.

To remove the partitions, it is only necessary to loosen screws *d*. The plates *c* can then be turned to one side, where they are out of the way, and the partitions withdrawn, throwing the three compartments into one of convenient size for bathing.

In order to render the vessel more suitable

and comfortable for bathing, I provide a removable head-rest, *f*, which can be readily placed in the end of the tub, giving to it the curved and sloping shape common and desirable in bath-tubs. This head-rest *f* is made of sheet-metal, preferably zinc, of the same depth and width as the tub, and provided at the top with a flange, *f'*, which embraces the edge of the tub, whereby the piece or rest *f* is held in place. One or more ribs, *f''*, should be placed at the back of the piece *f* to give it sufficient rigidity.

By the improvements described and claimed herein the set of wash-tubs may be readily and quickly converted into a bath-tub, and vice versa.

It is obvious that the precise details of construction described and shown need not be followed, but these may be varied without departing from the spirit of the invention.

I claim—

1. In combination with the tub or vessel, the removable head-rest having a curved and sloping shape, substantially as described.
2. A set of tubs separated by removable partitions so that they can be converted into a single tub or vessel, and provided with a removable head-rest, substantially as described.
3. The combination of the vessel or tub, the removable partitions provided with packing around their edges to render the same watertight, and the fastening devices comprising each a plate pivoted at one end to the side of the tub, and carrying in the other a set-screw for forcing the partition tightly against the sides of the tub, substantially as described.

In testimony whereof I have signed this specification in the presence of two subscribing witnesses.

JULIA B. FRENCH.
